UNITED STATES PATENT OFFICE.

CHARLES R. TOST, OF CRANSTON, RHODE ISLAND, ASSIGNOR TO THE HADLEY COMPANY,
OF PROVIDENCE, RHODE ISLAND.

BRACELET.

1,285,843.

Specification of Letters Patent.

Patented Nov. 26, 1918.

Application filed April 11, 1918. Serial No. 227,854.

To all whom it may concern:

Be it known that I, CHARLES R. Tost, a citizen of the United States, residing at Cranston, in the county of Providence and 5 State of Rhode Island, have invented a new and useful Improvement in Bracelets, of which the following is a specification.

This invention relates to certain new and useful improvements in a bracelet, having 10 particular reference to the individual link structure, and it has for its primary object to form the link in a simple and economical manner and at the same time to provide a construction which will be strongly reinforced and neat in appearance.

The invention further resides in an improved connection and spacer for the free ends of a pair of arms embodied in a link, as is hereinafter set forth in detail in the 15 following specification, succinctly defined in the appended claims, and illustrated in the accompanying drawings wherein—

Figure 1 is a longitudinal vertical section through a portion of a bracelet embodying 20 the present invention.

Fig. 2 is a longitudinal horizontal section of the same.

Fig. 3 is a plan of the blank from which the combined connector and spacer is constructed.

Fig. 4 is a side elevation of the connector shaped and ready for applying to the link body, and

Fig. 5 is a longitudinal horizontal section 35 of the link body, the free ends of which are joined together by the connector.

Referring more in detail to the drawings, the numeral 1 designates one end or base of a U-shaped link formed and stamped of 40 sheet metal to provide a pair of opposing channeled arms 2 which have their opposite ends free and spaced apart, the arms being substantially parallel so as to guidingly receive a connecting loop-like link 3. A projection 4 on the extremity of each arm 2, extends toward the opposite end of the link body and within the opposing hollow interiors of the arms, the free inner end portion 5 being deflected outwardly in a divergent 45 manner from the companion projection.

A combined connector and separator or spacer 6 of cruciform shape embodies a pair of oppositely extending wings 7 which have their outer end portions bent up and slightly 50 turned inwardly, as depicted in Fig. 4, for

embracing the projections 4. The remaining pair of oppositely extending wings 8 are rolled over to form a cylinder 9 which is designed to act as a sustaining spacer between the free ends of the link arms. 60

In applying the connector, the blank illustrated in Fig. 3 is bent and shaped substantially as depicted in Fig. 4 after which the wings 7 are positioned in the pockets 10. By applying pressure as with a pair of 65 pliers, the projections 4 and wings 7 will assume a secure and firm interlocking relation, and the outwardly facing cylinder 9 will be interposed between the adjacent ends of arms 2, serving not only as a sustaining 70 spacer but also providing a filler for such intervening space and affording a neat finish to the link.

As previously mentioned, these links are connected by a narrow link 3 which has one 75 end slidably engaged in the slot defined by arms 2 of one link body and the opposite end formed with lateral projections 11 designed to coöperate with the channels of the arms of the adjacent link body. 80

A cylinder 12, formed from a pair of wings that extend from the opposite sides of the base 1, acts as a sustaining spacer between the adjacent ends of the arms and also as a support for one end of a coiled 85 expansion spring 13 which is disposed within the links for exerting a force against that end of link 3 which has sliding engagement with the particular link body. Consequently, the coiled springs yieldably hold 90 the bracelet in its contracted form.

Each link has end reinforcement and a positive connection for the free ends of a U-shaped link body, which connection is simple and easily produced. The connector 95 is so embodied within the link structure as to prevent easy rupturing of the same, as well as being concealed from view.

Having thus described my invention, what I claim as new and desire to secure by Letters Patent is—

1. A link for bracelets, comprising a U-shaped body formed of sheet metal bent to provide a pair of spaced and opposing channeled arms having terminals that first extend inwardly, then toward the opposite end of the body and thence outwardly, a connector plate having two wings which extend inwardly and engage over the terminals for interlocking therewith, a joining link of loop 105 110

form guidingly received at one end between the arms of the body and adapted to be received between the arms of an adjacent body for connecting the two bodies, and a coiled 5 spring housed within the body for holding the joining link retracted.

2. A bracelet including a link comprising spaced side parts, and a cross-shaped connector plate having two opposite wings secured 10 to and connecting the side parts at one end, the remaining two wings terminating in tubular parts located between the side parts to serve as a sustaining spacer therefor.

3. A link for bracelets, comprising a U-shaped body formed of sheet metal bent to provide a pair of spaced and opposing channeled arms having terminals that first extend inwardly, then toward the opposite end of the body and thence outwardly, a connector plate of cruciform shape having two opposing wings which extend inwardly and engage over the terminals for interlocking therewith, the other two opposing wings terminating in tubular parts located between 20 the adjacent ends of the arms for sustaining the latter in spaced relation.

4. A link for bracelets, comprising a U-shaped body formed of sheet metal bent to provide a pair of spaced and opposing channeled arms having terminals that first extend inwardly then toward the opposite end of the body and thence outwardly, and means 25 for interlockingly connecting the projections

and positively holding the adjacent ends of the arms spaced apart.

5. A bracelet including a link comprising spaced side parts, an integral connection therebetween at one end, a connector plate located at the opposite end for connecting the side parts, and sustaining spacers carried 35 by the two means of connection.

6. In a bracelet, a link having spaced parts arranged side by side and formed at one end with inturned projections, a connecting member having inturned ends pressed into 40 interlocking relation with the projections, and means acting as a sustaining spacer between the spaced parts at said end.

7. A bracelet including a link comprising spaced sheet metal side parts having hollow 45 inner faces opposing one another, a joining loop for connecting adjacent links having one end operable between the side parts of each link, and an expansion spring of greater diameter than the space between the edges of 50 the side parts, said spring disposed within the hollow inner face of the latter and acting to hold the bracelet contracted.

In testimony whereof I have signed my name to this specification in the presence of 55 two subscribing witnesses.

CHARLES R. TOST.
